UNITED STATES PATENT OFFICE.

JULIUS G. BURNS AND HERBERT S. DAVIS, OF NEW YORK, N. Y., ASSIGNEES TO
PURECOLD PRODUCTS OF AMERICA, INC., A CORPORATION OF DELAWARE.

REFRIGERATING HOUSEHOLD UNIT.

Application filed February 23, 1926. Serial No. 90,094.

This invention relates to refrigerating household units, particularly of the type used to refrigerate ice for table use, and an object of this being to provide a novel, and 5 highly efficient non-complicated apparatus conveniently arranged to use prepared solidified carbon dioxide snow as the refrigerant.

For further comprehension of the invention, and of the objects, and advantages thereof, reference will be had to the following description and accompanying drawing, and to the appended claims in which the various novel features of the invention are 15 more particularly set forth.

Referring to the drawing which forms a part of this disclosure:

Fig. 1 is a horizontal sectional view taken on the line 1—1 of Fig. 2.

20 Fig. 2 is a vertical sectional view taken on the line 2—2 of Fig. 1.

Fig. 3 is a top detailed view of the lower drawer.

25 Fig. 4 is a modification illustrating the employment of means to aid in the opening of the drawer.

Fig. 5 is a view similar to Fig. 1, but of a modified construction.

30 The housing 10 is of rectangular cross-section, and at the upper central portion is provided with a sunk-in portion 10^a to support and house a receptacle inserted therein, such as 11, formed with projections 11^a from the sides therefor to obtain a clearance space 35 between the walls of the receptacle and the housing 10.

The refrigerant is placed in the receptacle 11, and the refrigerant used is prepared solidified carbon dioxide snow, which may be 40 entered into the snow receptacle by means of a nozzle entering into the mouth 11^b, which thereafter is closed, said nozzle being connected to a supply of liquid carbon dioxide, with the necessary control valves interposed. The liquid carbon dioxide must be under a high pressure, and its expansion through the nozzle from high pressure to a gas at atmospheric pressure refrigerates a certain portion into carbon dioxide snow. 45 The snow thus formed being porous, may then be compressed to obtain a greater amount in a given space, to a density even greater than ice.

50 Upon the absorption of heat by the snow 55 it turns into a gas, and the receptacle 11

is provided with a plurality of apertures 11^c in the side walls and bottom thereof, to allow the escape of the said gas.

The inner space of the housing 10, is partially filled with brine 14, which surrounds the sunk-in portions 10^a, to better radiate the coolness, and this brine may be entered by means of a suitable inlet pipe, and union indicated at 15, the faucet 16 being provided at the bottom portion of the housing holding the brine, to permit of removing the same.

It is known that heat rises, and relatively speaking coldness falls, therefore in the bottom of the housing 10, a chamber 10^b is 70 formed, which has a door 17, hinged as at 18, and at the upper end provided with locking means, indicated at 19. Slidably mounted within this chamber is a drawer 20, divided by partitions 21 into a plurality of 75 compartments opened at the top.

The drawer 20 may be slid out, and these compartments filled with water, thereafter the drawer being reinserted, and the door 17 closed. The water may thus be frozen 80 into cubes of ice, which may be used for table purposes.

In the modification illustrated in Fig. 4 means is provided to automatically project the drawer 20' when the door 17 is opened, 85 the drawer 20' being of shorter length than the housing so as to provide a space in the rear for the action of a spring 22, co-acting between the rear of the drawer, being attached thereto against a flange 23, and an 90 adjustable resistance formed by a flange 24 to which the spring is attached, and a stud 25 fixed to said flange and operating in a threaded aperture in the rear of the housing, and provided with a locking bolt 26 thereon. 95

In the modification illustrated in Fig. 5 it is shown that the snow chamber may extend the full length of the device, and the brine being stored on both sides of the chamber in suitable compartments 10^b. 100

The functioning of this device is very obvious from the above description.

While we have illustrated and described our invention with some degree of particularity, we realize that in practice various 105 alterations therein may be made. We therefore reserve the right and privilege of changing the form of the details of construction, or otherwise altering the arrangement of the correlated parts, without de- 110

parting from the spirit or the scope of the appended claims.

Having thus described our invention, what we claim as new, and desire to secure 5 by United States Letters Patent is:—

1. A refrigerator household unit, adapted to refrigerate ice for table use, comprising a housing of rectangular cross-section, having at the upper portion a sunk-in member, 10 supporting a receptacle housing prepared solidified carbon dioxide snow, and provided with apertures to allow the escape of gas, said housing being formed with a brine chamber surrounding the sunk-in member, 15 and a lower chamber, closed by a door, and housing a drawer with partitions to hold water to be turned into ice cubes, and means to project said drawer upon the opening of said door.
2. A refrigerator household unit, adapted to refrigerate ice for table use, comprising a housing of rectangular cross-section, having at the upper central portion a sunk-in member, supporting a receptacle housing 20 prepared solidified carbon dioxide snow, and provided with apertures to allow the escape of gas, said housing being formed with a brine chamber surrounding the sunk-in member, and a lower chamber, closed by a 25 door, and housing a drawer with partitions to hold water to be turned into ice cubes, and means to project said drawer upon the opening of said door, said means consisting of a spring acting between said drawer, and an adjustable resistance.
3. A refrigerator household unit, adapted to refrigerate ice for table use, comprising a housing of rectangular cross-section, having at the upper central portion a sunk-in member, supporting a receptacle housing 30 prepared solidified carbon dioxide snow, and provided with apertures to allow the

escape of gas, said housing being formed with a brine chamber surrounding the sunk-in member, and a lower chamber, closed by 45 a door, and housing a drawer with partitions to hold water to be turned into ice cubes, and means to project said drawer upon the opening of said door, said means consisting of a spring acting between said drawer, and an adjustable resistance, formed by a stud acting in a threaded aperture in said housing, and a co-acting lock nut.

4. A refrigerator household unit, adapted to refrigerate ice for table use, comprising 50 a housing, a sunk-in portion provided in said housing, a receptacle housing prepared solidified carbon dioxide snow supported in said sunk-in member, a brine chamber surrounding said sunk-in portion, a lower 55 chamber formed in said housing, a door communicating with said lower chamber, a drawer formed with partitions housed in said lower chamber, and means to project said drawer upon the opening of said door.

5. A refrigerator household unit, adapted to refrigerate ice for table use, comprising a housing, a sunk-in portion provided in said housing, a receptacle housing prepared solidified carbon dioxide snow supported in 60 said sunk-in member, a brine chamber surrounding said sunk-in portion, a lower chamber formed in said housing, a door communicating with said lower chamber, a drawer formed with partitions housed in 65 said lower chamber, and means to project said drawer upon the opening of said door, said means consisting of a spring acting between said drawer, and an adjustable resistance.

In testimony whereof we have affixed our signatures.

JULIUS G. BURNS.
HERBERT S. DAVIS.
